UNITED STATES PATENT OFFICE.

VICTOR H. ANDERSON, OF MOUNT VERNON, MAINE.

ROTARY ENGINE-VALVE.

1,190,363.

Specification of Letters Patent. Patented July 11, 1916.

Application filed September 4, 1915. Serial No. 48,998.

To all whom it may concern:

Be it known that I, VICTOR H. ANDERSON, a citizen of the United States, residing at Mount Vernon, in the county of Kennebec 5 and State of Maine, have invented new and useful Improvements in Rotary Engine-Valves, of which the following is a specification.

This invention relates to rotary valves for 10 internal combustion engines of the multiple cylinder type, the object in view being to produce a valve of the class specified which is adapted to take care of the intake and exhaust of a multiple cylinder engine each 15 cylinder of which only requires a single port to take care of both the intake and exhaust of the fresh mixture and burned gases.

One of the chief objects of the present invention is to produce a valve of the character 20 stated in which there are self-contained intake and exhaust manifolds, whereby the inflowing cool mixture will be heated by the burned gases upon their movement through the valve to the exhaust chamber.

25 A further object of the invention is to produce a valve of the class above defined, the construction of which renders it reliable and efficient, enables the same to be lubricated without permitting the lubricant to 30 enter the engine, which effectively excludes foreign matter, and which may be driven with a very small percentage of power of the engine.

With the above and other objects in view, 35 the invention consists in the novel construction, combination and arrangement of parts, as herein described, illustrated and claimed.

In the accompanying drawings: Figure 1 is a cross section through a multiple cylinder engine embodying the present invention. Fig. 2 is a horizontal section on the line 2—2 of Fig. 1. Fig. 3 is a plan view of the inner portion of the valve including the valve shaft, the manifold forming partition, and other parts intimately associated with the valve shaft. Figs. 4, 5 and 6 are, respectively, sections on the lines 4—4, 5—5 and 6—6 of Fig. 2, omitting all parts except the valve itself. Fig. 7 is a section on the 50 line 7—7 of Fig. 2. Fig. 8 is a detail view of one of the packing rings.

Referring primarily to Figs. 1 and 2, the engine illustrated in the drawings is seen to be of the multiple cylinder type, the cylinders A and B being arranged at opposite 55 sides of the valve chamber which is indicated at C, the last named chamber being therefore located between the oppositely arranged cylinders A and B which are shown for convenience as arranged at an angle to 60 each other forming what is known as a multiple cylinder engine of the V type. As shown, the cylinders A and B, four in number, are arranged at an acute angle to each other but it will of course be understood 65 that the angle between the cylinders A and B may be varied to suit the will of the manufacturer and that, if desired, the said cylinders A and B may be arranged vertically or in parallel relation to each other. 70

The main feature of the invention resides in the valve which is designated generally at D, the same comprising a central shaft 1, and an outer cylindrical tubular shell 2, the medial portion 3 and the extreme end portions 4 of which are shown as imperforate. The portions 5 and 6 lying at opposite sides of the medial portion 3 are provided each with an inlet port and an exhaust port, the portion 5 at one side comprising the inlet 80 port 7 and the exhaust port 8, while the ported portion at the opposite side of the imperforate medial portion 3 is formed with an inlet port 9 and an exhaust port 10. In view of the fact that the valve as a whole 85 is adapted for use in connection with a four cycle engine and therefore revolves at one half the speed of the engine shaft, the intake and exhaust ports at one side of the central portion 3 are arranged substantially at 90 ninety degrees apart so that the exhaust stroke will be followed by the intake stroke, the remainder of the shell in line with said ports being imperforate for approximately one hundred and eighty degrees so as to provide for the compression and firing strokes. Furthermore, the ports 9 and 10, collectively, are arranged ninety degrees from the ports 7 and 8 so that the explosions in the four cylinders will follow each other successively.

11 designates a manifold forming parti-

tion or web extending longitudinally of the shaft 1 and shell 2 and also diametrically of said members, said partition reaching from the shaft 1 to the inner wall of the shell 2.

5 At one end of the valve, the partition 11 connects with a semi-circular end wall 12 which incloses one half of the respective end of the shell 2 and at the other end of the valve, the partition 11 is connected to a 10 similar semi-circular end wall 13 which closes one half of that end of the cylinder. Between its ends, the partition or web 11 is given a quarter twist at 14, said twisted portion of the partition or web lying within the 15 imperforate medial portion 3 of the shell 2. This quarter twist of the web or partition 11 is required in order to receive and deliver the fresh mixture to the cylinders and also to receive and discharge the burned gases 20 therefrom. The shell 2 is supported by means of the end walls 12 and 13 and the outer edges of the partition or web 11 including the angular or twisted portions 14 thereof.

25 The shaft 1 is journaled in bearing members 15 and 16 and is provided at one end with a squared or non-circular portion 17 on which is mounted a silent chain wheel 18 from which a silent driving chain extends 30 to the crank shaft of the engine. On the same squared portion 17 of the shaft is mounted a fan belt pulley 19 held in place by a nut 20. The wheel 18 is formed with an extended hub 21 forming another journal 35 which is mounted in a bearing member 22; the bearing members 15, 16 and 22 forming parts of the engine frame. At the opposite end the shaft 1 has fast thereon a silent chain wheel 23 from which a chain 40 extends to the magneto shaft. Keys 24 are employed to securely lock the wheels 18 and 23 to the shaft 1. The shaft 1 is further provided with flanges or collars 25 and 26 beyond the ends of the valve, said collars 45 working against the adjacent end walls of the valve chamber so as to prevent leakage of mixture or burned gases from the valve chamber at said points and also to prevent the oil from the journals 15 and 16 from 50 entering the intake chamber 27 and the exhaust chamber 28 to which are connected suitable intake and exhaust pipes as may be found convenient.

Oil is introduced through an opening 29 55 into a groove 30 in the inside of the valve chamber wall where it enters an annular series of oil grooves 31 in the outer face of the imperforate medial portion 3 of the shell, the oil being conducted through the 60 grooves 31 to other grooves 32 and 33 in a pair of skeleton shaped packing rings surrounding the ported portions 5 and 6 of the valve shell so as to produce a snug fit be-

tween the valve and its containing casing, preventing the lubricating oil from reaching the intake and exhaust ports and also preventing leakage of the mixture and exhaust gases at such points.

In operation, it will be understood that the valve as a whole hereinabove described 65 may be operated or revolved at one half the speed of the engine shaft, requiring but a very small percentage of the engine power. The timing of the intake and exhaust is fixed and therefore invariable so that the 70 very best results may be obtained as regards the power and general efficiency of the engine. Furthermore, the valve is silent and smooth in its operation. The inlet and exhaust manifolds are self-contained within 75 the shell of the valve and thus the incoming mixture is heated by the exhaust, producing at all times a good explosive mixture, resulting in better combustion, increased power and reduction in the accumulation 80 of carbon in the engine cylinders and on the heads of the pistons. It will be observed that there is only one port in each cylinder, which port takes care of both the inlet of the charges and the exhaust of the 85 burned gases. Under the arrangement of the valve in its relation to the engine cylinders as hereinabove described, the valve itself is protected from the highest temperatures which occur within the cylinders at 90 the time the explosions take place.

Having thus described my invention, I claim:—

1. In a multiple cylinder V-type internal combustion engine, the combination of angularly related cylinders, a valve chamber located between the angularly related cylinders and formed with a cylindrical bore and a single port for each cylinder acting both as an intake and exhaust port, a rotary cylindrical valve mounted to revolve in said chamber and embodying a tubular shell having an imperforate medial portion and ported portions at opposite sides of said medial portion, each formed with an inlet 100 port and an exhaust port which successively register with the ports of the said cylinders, an intake chamber at one end of said valve, an exhaust chamber at the other end of said valve, and an internal partition extending longitudinally and diametrically of 105 said shell and shaft and forming valve-contained intake and exhaust manifolds.

2. In a multiple cylinder V-type internal combustion engine, the combination of angularly related cylinders, a valve chamber located between said angularly related cylinders and formed with a cylindrical bore and a single port for each cylinder acting both as an intake and exhaust port, a rotary cylindrical valve mounted to revolve 110

in said chamber and embodying a tubular shell having an imperforate medial portion and ported portions at opposite sides of said medial portion, each formed with an inlet port and an exhaust port which successively register with the ports of the respective cylinder, and an internal partition extending longitudinally and diametrically of said

shell and forming valve-contained intake and exhaust manifolds. 10

In testimony whereof I affix my signature in presence of two witnesses.

VICTOR H. ANDERSON.
